US00D959005S

(12) **United States Design Patent** (10) **Patent No.:** **US D959,005 S**
Peterson (45) **Date of Patent:** **** Jul. 26, 2022**

(54) **ELONGATED SKIN TONING DEVICE**

(71) Applicant: **Carol Cole Company**, Vista, CA (US)

(72) Inventor: **Tera Peterson**, Carlsbad, CA (US)

(73) Assignee: **Carol Cole Company**, Vista, CA (US)

(**) Term: **15 Years**

(21) Appl. No.: **29/698,776**

(22) Filed: **Jul. 19, 2019**

Related U.S. Application Data

(63) Continuation of application No. 29/647,759, filed on May 15, 2018, now Pat. No. Des. 854,699.

CLAIM

The ornamental design for an elongated skin toning device, as shown and described.

DESCRIPTION

FIG. 1 is a front perspective view of the elongated skin toning device;

FIG. 2 is a front elevational view of the elongated skin toning device shown in FIG. 1;

FIG. 3 is a rear elevational view of the elongated skin toning device shown in FIG. 1;

FIG. 4 is a right side elevational view of the elongated skin toning device shown in FIG. 1;

FIG. 5 is a left side elevational view of the elongated skin toning device shown in FIG. 1;

FIG. 6 is a top plan view of the elongated skin toning device shown in FIG. 1;

FIG. 7 is a bottom plan view of the elongated skin toning device shown in FIG. 1; and,

FIG. 8 is a rear perspective view of the elongated skin toning device shown in FIG. 1.

The broken lines in the drawings depict portions of the elongated skin toning device and form no part of the claimed design.

1 Claim, 5 Drawing Sheets
